Specification for Design.

Patented Jan. 6, 1914.

Application filed July 25, 1913. Serial No. 781,246. Term of patent 7 years.

To all whom it may concern:

Be it known that I, GEORGE P. ALTENBERG, a citizen of the United States, residing at Cincinnati, in the county of Hamilton and State of Ohio, have invented a new, original, and ornamental Design for a Metal Casing for Vacuum-Insulated Carafes, of which the following is a specification, reference being had to the accompanying drawing, forming part thereof.

My new, original and ornamental design for a metal casing for vacuum insulated

carafes is shown in the accompanying drawing, in which:

Figure 1 is a side elevation of the casing; and, Fig. 2 is a plan view of the same.

I claim:

The ornamental design for a metal casing for vacuum insulated carafes, as shown.

GEORGE P. ALTENBERG.
